WO WO 2010/019035 A1 2/2010

Primary Examiner — Marianne Pandozzi*Assistant Examiner* — Jae Liang*Attorney, Agent, or Firm* — Alston & Bird LLP(57) **CLAIM**

The ornamental design for a connector, as shown and described.

DESCRIPTION

FIG. 1 is a perspective view of a connector showing our new design;

FIG. 2 is a front elevation view thereof;

FIG. 3 is a left side elevation view thereof;

FIG. 4 is a right side elevation view thereof;

FIG. 5 is an enlarged bottom plan view thereof; and,

FIG. 6 is an enlarged top plan view thereof.

The broken lines immediately adjacent shaded areas represent bounds of the claimed design, while all other broken lines are unclaimed features. The broken lines form no part of the claimed design.

1 Claim, 6 Drawing Sheets(56)
